[57] CLAIM

The ornamental design for a novelty Santa Claus ball golf ball figure, as shown.

DESCRIPTION

FIG. 1 is a front elevational view of a novelty Santa Claus golf ball figure showing my new design;
FIG. 2 is a rear elevational view;

FIG. 3 is a left side elevational view;
FIG. 4 is a right side elevational view;

FIG. 5 is a top elevational view;
FIG. 6 is a bottom plan view;
FIG. 7 is a front elevational view of a second embodiment thereof;
FIG. 8 is a rear elevational view of the embodiment of FIG. 7;
FIG. 9 is a left side elevational view of the embodiment of FIG. 7;
FIG. 10 is a right side elevational view of the embodiment of FIG. 7;
FIG. 11 is a top plan view of the embodiment of FIG. 7;
FIG. 12 is a bottom plan view of the embodiment of FIG. 7;
FIG. 13 is a front elevational view of a third embodiment thereof;
FIG. 14 is a rear elevational view of the embodiment of FIG. 13;
FIG. 15 is a left side elevational view of the embodiment of FIG. 13;
FIG. 16 is a right side elevational view of the embodiment of FIG. 13;
FIG. 17 is a top plan view of the embodiment of FIG. 13;
FIG. 18 is a bottom plan view of the embodiment of FIG. 13;
FIG. 19 is a front elevational view of a fourth embodiment thereof;
FIG. 20 is a rear elevational view of the embodiment of FIG. 19;
FIG. 21 is a left side elevational view of the embodiment of FIG. 19;
FIG. 22 is a right side elevational view of the embodiment of FIG. 19;
FIG. 23 is a top plan view of the embodiment of FIG. 19;
FIG. 24 is a bottom plan view of the embodiment of FIG. 19.
